Specification for Design.

Patented Dec. 26, 1911.

Application filed June 5, 1911. Serial No. 631,467. Term of patent 14 years.

To all whom it may concern:

Be it known that I, JONATHAN A. HASKELL, a citizen of the United States, residing in Middletown township, Monmouth county, State of New Jersey, have invented a new, original, and ornamental Design for Imitation-Leather Fabrics or Similar Articles, of which the following is a specification, reference being had to the accompanying drawing, which forms a part thereof.

The drawing shows in plan a portion of an imitation leather fabric embodying my design.

I claim:

The ornamental design for an imitation leather fabric or similar article, as shown.

In testimony of which invention, I have hereunto set my hand, at New York city, on this 25th day of May, 1911.

JONATHAN A. HASKELL.
